UNITED STATES PATENT OFFICE

EDWIN DARBY, OF BIRMINGHAM, ENGLAND

APPARATUS FOR HEATING LIQUIDS

Application filed November 23, 1929, Serial No. 409,326, and in Great Britain November 29, 1928.

This invention relates to apparatus for heating liquids, and is intended primarily for household use, and refers to that known type of apparatus which includes a boiler 5 having inlet and outlet openings for connection to a tank or liquid supply pipe, the boiler being usually provided with a dished or concave base under which a burner or other heater can be placed a number of tubular flues 10 being provided connecting the hollow interior of the boiler in which the burner is situated with the outer atmosphere, these flues passing through the space occupied by the liquid, and thereby imparting to the liquid 15 a certain additional amount of heat.

The object of the present invention is to provide apparatus for heating liquids of a generally improved construction.

Referring to the drawings:—

20 Figure 1 is an exterior view in side elevation.

Figure 2 is a sectional view.

Figure 3 is a perspective view of a part of the apparatus shown in Figures 1 and 2.

25 Figure 4 is a horizontal section on line 4—4 of Figure 2.

In the construction illustrated, the boiler 1 is shown applied to the side of a water tank 2. This water tank 2 may be of any 30 suitable shape, and it may either have an open top or a closed top. Further, the supply of water to the tank 2 may be governed by a float valve, or by any other means. The boiler may be applied directly to a liquid 35 supply pipe.

The arrangement is such that water is heated in the boiler 1 and passes to the tank 2. In any arrangement the pipes may be connected to the tank 2 so that the hot water 40 can be taken to one or more required positions.

The boiler 1 has a cylindrical body 3 and an upwardly domed top 4.

At one side is a horizontal water inlet 5 and near the top is an inclined water outlet 6.

45 The lower part of the body 3 is provided with an integral flange 7 to which is attached an upwardly domed or hollow member 8, the member 8 having a flange 9 by which it is bolted to the flange 7, suitable jointing ma-

terial preferably being placed between the two flanges.

Further, upon the interior the boiler body 3 may be screw threaded, as shown at 10, while the exterior of the base member 8 may be similarly threaded so that the one part 55 screws into the other.

The base member 8 is provided with a central upwardly extending flue 11 which screws into a boss 12 in the boiler top, and if required a number of additional flues 13 may be provided leading from the base member 8 60 into the flue 11.

A gas burner 14 is placed beneath the boiler base and beneath and enclosing this gas 65 burner is a shield 15 attached to the flanges 7 and 9 by the bolts 16.

The shield 15 is provided with openings 17 so that when condensed water collects in the shield the level thereof cannot reach the 70 upper part of the burner 14. The upper edges of the openings 17 may be pressed or disposed inwardly so as to direct any drip onto the inner surface of the shield.

The shield 15 may be used as a support for 75 the burner, the burner tube 18 being brazed or soldered to the tube, as shown at 19.

In the construction illustrated I have shown the boiler body and base as castings, but it is to be understood that either or both 80 of these parts may be made as metal pressings or stampings, in which case the necessary screw threads may be rolled or may be dispensed with, brazing or welding being employed instead of the screw joints. 85

The inlet and outlet openings 5 and 6 are connected to the tank 2 respectively by pipes 20 and 21, the pipe 21 being arranged in an inclined position so that the hot water will 90 flow more freely into the tank 2.

The apparatus, in addition to providing a means of obtaining a supply of hot water or other liquid, may be used for heating the water in a cold water tank or pipe, to prevent 95 freezing at a minimum of cost and trouble.

What I claim then is:—

1. A liquid heating unit for application to a tank or supply pipe, comprising an outer shell domed at its upper end and internally 100 screw threaded and externally and circum-

ferentially flanged at its lower end, the domed end having a central internally screw threaded hole, a body member placed in said outer shell in spaced relation thereto, said body having a recessed or upwardly domed lower end forming a combustion chamber, a vertical central tube projecting upwardly from said domed end and forming a central flue, a series of secondary tubes forming auxiliary flues, each partly vertical and partly radial, and all arranged around the central flue and each communicating at one end with the central flue and at the other end with the combustion chamber, a circumferential flange on said body, an external screw thread on said body adapted to engage the internal thread of the said shell, means for securing the flange of the shell to the flange of the body, said central tube being screw threaded at its upper end and adapted to screw into the threaded hole in the outer shell, and all of the said flues passing through the space provided between the body member and the shell, an inlet and an outlet for said space between the shell and the body member, and a heating unit in said combustion chamber.

2. A liquid heating unit for application to a tank or supply pipe, comprising an outer shell domed at its upper end and internally screw threaded and externally and circumferentially flanged at its lower end, the domed end having a central internally screw threaded hole, a body member placed in said outer shell in spaced relation thereto, said body having a recessed or upwardly domed lower end forming a combustion chamber, a vertical central tube projecting upwardly from said domed end and forming a central flue, a series of secondary tubes forming auxiliary flues, each partly vertical and partly radial, and all arranged around the central flue and each communicating at one end with the central flue and at the other end with the combustion chamber, a circumferential flange on said body, an external screw thread on said body adapted to engage the internal thread of the said shell, means for securing the flange of the shell to the flange of the body, said central tube being screw threaded at its upper end and adapted to screw into the threaded hole in the outer shell, a shield adapted to enclose the heating unit and collect the products of condensation, the shield having an opening disposed below the heating unit to prevent the products of condensation interfering with the operation of the heating unit and also serving as an inlet to the combustion chamber.

3. In a heating apparatus of the type specified an inner body having a dished or domed plate member adapted to form the roof of the combustion chamber, a vertical central tube projecting upwardly from said domed end and forming a central flue, a series of secondary tubes forming auxiliary flues, each

partly vertical and partly radial and all arranged around the central flue, and each communicating at one end with the central flue and at the other end with the combustion chamber, the said tubes forming the flues and the domed plate member all being formed integrally, and all of the said flues passing through the space provided between the body member and the shell, a circumferential flange on said body, an external screw thread on said body adjacent the said flange, and a screw thread on the upper end of said central tube.

4. A liquid heating unit for application to a tank or supply pipe, comprising an outer shell domed at its upper end, a body member placed in said outer shell in spaced relation thereto, the space between said body and outer shell forming a liquid receptacle, said body having a domed lower end forming a combustion chamber, a vertical central flue tube projecting upwardly from said combustion chamber and projecting through said outer shell, a plurality of auxiliary flue tubes connecting the central flue with the combustion chamber, the body portion together with the central main flue pipe and auxiliary flue pipes being detachable from the outer shell the outer shell having means at its upper and lower ends for connection to a tank or supply pipe and a heating unit in said combustion chamber.

In witness whereof I affix my signature.
EDWIN DARBY.
